UNITED STATES PATENT OFFICE.

WILLIAM A. LOUDON, OF CHICAGO, ILLINOIS, ASSIGNOR TO GENERAL ELECTRIC COMPANY, A CORPORATION OF NEW YORK.

TURBINE-CONTROLLER.

941,426.

Specification of Letters Patent. Patented Nov. 30, 1909.

Application filed February 4, 1904. Serial No. 192,047.

To all whom it may concern:

Be it known that I, WILLIAM A. LOUDON, a citizen of the United States, residing at Chicago, in the county of Cook and State of Illinois, have invented a new and useful Fluid-Actuated Turbine-Controller, of which the following is a specification.

My invention relates to improvements in controllers or governors for turbines which are driven by a pressure of water, steam or gas, and particularly for that class which have a series of jets or nozzles by means of which a series of streams of the pressure fluid are forced against or into a series of pockets or paddles on a rotating portion of the turbine. The force of these streams causes the turbine wheel to rotate, and to reduce the speed of said turbine wheel when the load decreases, one or more streams, as may be required, are completely shut off, and if a greater speed or more power is required, more of the aforesaid streams are brought into use.

The object of my invention is to provide a mechanism whereby these streams are automatically shut off or turned on as may be required to keep the turbine wheel rotating at a certain predetermined speed.

I do not claim this mechanism in connection with any particular kind of turbine, hence I do not attempt to illustrate the interior of a turbine, but only a general elevation of one class of turbine so as to show the approximate location and connections of the different elements constituting my invention; and I see no reason why my improved controller can not be applied to any kind of engine, by making such changes as would require only the services of a skilled mechanician.

My invention consists broadly of attaching a liquid pump to the turbine shaft so that the pump will force liquid through a pipe provided therefor, and utilizing this liquid pressure to operate the valves controlling the speed of the turbine; a by-pass of a certain size being provided whereby the liquid forced by the pump is returned to a supply reservoir. This by-pass I prefer providing with a regulating valve, so as to regulate the amount of liquid which is to flow through said by-pass and thereby regulate the speed of the turbine. I also preferably place another valve in the aforesaid by-

pass which is constantly being controlled by a governor driven by the turbine.

To more fully describe my invention I have illustrated the same in the accompanying three sheets of drawings, in which—

Figure 1, is a side elevation of a turbine showing my invention in connection therewith; Fig. 2, is a diagrammatic view showing the apparatus constituting a portion of my invention; Fig. 2^a, is a view partly in section showing a modification of a part of my invention; Fig. 3, is a detail sectional view showing a modified form of a portion of my invention; Fig. 4, is a detail-sectional view of a valve mechanism used in connection with my invention, and Fig. 5, is a similar view showing a modified form of the valve mechanism shown in Fig. 4.

Similar reference characters refer to similar parts throughout the several views.

The style of turbine which I have shown in the drawing is mounted on a vertical shaft which extends some distance above the turbine and has secured thereto a dynamo electric machine, the two machines being enclosed in a proper casing 10. Driven by the turbine shaft and preferably mounted on the same at the top of the casing 10 is a liquid pump 11. This pump 11 has a suction pipe 12 and the discharge pipe 13. The suction pipe 12 extends into a liquid receptacle 14 preferably near to the bottom thereof; and the receptacle 14 is preferably open on top so as to be exposed to the atmospheric pressure for reasons to be mentioned. The discharge pipe 13 is provided with any suitable arrangement of piston and cylinder whereby a plurality of rods are operated successively by the increased pressure in the discharge pipe 13.

A pipe 15 serving as a bypass is connected to the discharge pipe 13 and leads therefrom to the receptacle 14.

When the pump 11 is in operation the liquid will be drawn from the receptacle 14 through the suction pipe 12 and pump 11, and forced through the discharge pipe 13, and finding no other exit will pass through the bypass 15 and back into the receptacle 14.

If the bypass 15 were of the same area in cross section as the discharge pipe 13, there would, of course, be no perceptible pressure in the pipe 13.

As one of the objects of my invention is to

utilize the pressure created by the pump 11 to operate certain valves I provide in the bypass 15 an ordinary globe valve 16, by means of which the passage of liquid through 5 the bypass 15 can be regulated.

The final object in creating a pressure in the pipe 13 is to operate a plurality of valves which control the steam supply to the turbine for driving the same.

10 I have shown two systems of operating these steam supply valves from the pressure in the discharge pipe 13, the one shows the steam supply valves operated electrically and the other shows the steam supply valves 15 operated directly by the pressure of the liquid in pipe 13.

I will describe the former system first and then the latter.

20 A branch of the discharge pipe 13 is connected to one end of a cylinder 17 which has fitted into it a piston 18 on the end of a piston rod 19 which extends through a hole in a screw cap 20 in the other end of the cylinder 17. A coiled compression spring 21 is 25 interposed between the piston 18 and the screw cap 20 to normally hold the piston at the end of the cylinder 17 where the pipe 13 is connected.

30 Any pressure created in the pipe 13 will therefore be exerted against the piston 18 and compress the spring 21 partly; of course, the greater the pressure is, the greater the compression of the spring will be.

35 The outer end of the piston rod 19 is provided with a metallic contact piece 22, arranged to move and be contacted with a double series of spring pressed carbon brushes 23, arranged to contact with the metallic piece 22 in pairs. The metallic piece 40 22 serves to make electrical contact between each pair of carbon brushes 23 successively as it is moved along. One of each pair of brushes 23 is connected by a conductor 24 to one side of a battery or source of electric current 25, while the remaining one of each 45 pair of brushes 23 is connected by a conductor 26 to the coil of a solenoid 27, the opposite end of the said solenoid coil being connected by a conductor 28 to the opposite side of the battery 25. Obviously it takes more force to compress the spring 21 a great 50 distance than it does to compress it only slightly.

55 When no pressure is exerted against the piston 18 by the liquid in the discharge pipe 13 the piston and therefore the contact piece 22 are held in their normal position by the spring 21, in which position the contact piece 22 does not contact with any of 60 the brushes 23. When pressure is exerted against the piston 18 by the liquid contained in the discharge pipe 13 the piston will be moved against the pressure of the spring 21, first to cause the metal piece 22 to contact 65 with the first pair of brushes 23 of the

series; thus closing the circuit through one brush 23, conductor 26, solenoid 27, conductor 28, battery 25, conductor 24 and to the other brush 23. The closing of this circuit causes the solenoid core 29 to be attracted and moved downward, which carries with it the operating rod 30 which is connected to the operating lever 31 of a small pilot valve 32.

A greater pressure exerted against the 75 piston 18 by the liquid in the pipe 13 will make contact between the second pair of brushes 23 of the series, which will cause the second valve 32 of a series, to be moved by the second solenoid of a series. And so on 80 a still greater pressure will cause the third solenoid of the series to operate the third valve 32 of a series.

It is understood that any other electrical appliance which will operate the valves 32 85 is an equivalent of that just described.

The pilot valve 32 is a small valve auxiliary to the pressure fluid supplying valve. To reduce the load on the controlling or governing mechanism to a minimum, I arrange 90 the pressure fluid or supply valve to be moved by the motive fluid under the control of said valve 32. As all of the regulating or supply valves are the same, I will only describe one of them.

95 Referring to Fig. 4, and assuming the pressure fluid to be steam, the main steam pipe 33 is connected with the smaller steam pipe 34, by a passage-way provided with the valve 35 which is held firmly on its seat by the pressure in pipe 33.

Rigidly secured to the valve 35 is a stem 36 which extends across the pipe 33 and has secured to it a piston 37 fitted to move in a cylinder 38.

105 Leading from the cylinder space 38 back of the piston 37, to the main steam pipe 33 is a small pipe 39 which is provided with the pilot valve 32. The pilot valve 32 is a three-way valve, and in one position it makes 110 communication between the main steam pipe 33 and the cylinder 38, as shown in Fig. 4, this being its operating position and results in closing a supply valve; in its other position it shuts off communication between the main steam pipe 33 and cylinder 38 and makes communication between the cylinder 38 and the outside atmosphere or other exhaust, this being its normal position and results in opening a supply valve.

115 A spring 40 is provided to form a cushion between the piston 37 and the end of the cylinder 38, which also assists in starting the piston and valve into motion.

I preferably provide the supply valve 35 120 with a piston end 41 to enter a dash-pot 42 which forms a cushion at one end of the valve stem 36.

125 The pipe 34 serves to convey the steam to a nozzle not shown.

In operation, when the pilot valve 32 is in its normal or open position, *i. e.* making communication between the cylinder 38, and the outside atmosphere, the steam pressure in the pipe 33 will force the piston 37 out against the spring 40 and hold the supply valve 35 off of its seat, permitting steam to pass into the pipe 34, and thence to the nozzle, or other fluid-discharging device. 5 Of course, it will be understood, to have this action of the parts take place the piston 37 must be of a greater area than the valve 35. In order to close the supply valve when the load decreases, the solenoid is deenergized 15 and the pilot valve caused to assume the position shown in Fig. 4 by a spring or other means. This admits live steam back of the piston and the pressure plus that of the spring 40 overcomes the pressure in the 20 steam pipe 33, and the piston moves downward and closes the supply valve.

In Fig. 5, I have shown a modification of the system of operating the supply valve 35; the piston 37 being provided with a perforation 43 which is considerably smaller than the opening in the pilot valve 32, and the cylinder space 38 is never brought into communication with the steam pipe 33.

In operation, when the pilot valve 32 is 30 in its normal or open position, *i. e.* making communication between the cylinder 38 and the outside atmosphere, the steam pressure in the pipe 33 will force the piston 37 out against the spring 40 and hold the supply 35 valve 35 off of its seat permitting steam to pass into the pipe 34.

I prefer to have an extension 44 on the piston 37 which will close the opening leading to the pilot valve 32 when such valve 40 is in its normal position, and thus prevent the escape of any steam through the perforation 43.

Referring to Fig. 2^a, the other system of operating the pilot valves 32 consists 45 of connecting a branch pipe 45 to the pipe 13 which connects with a series of cylinders 46 each provided with a piston 47 secured to a piston rod 48, which may be direct-connected to a supply valve or to a pilot 50 valve.

Each piston 47 is normally held in against the pressure in the pipe 13 by a coiled compression spring 49 interposed between the piston 47 and a screw cap 50 on the end of 55 the cylinder 46. The cylinders 46 are made successively smaller in diameter, so that as the pressure in the pipe 13 increases, the pistons 47 will successively be forced out against the springs 49, which are all of the same 60 tension.

The piston rods 48 are connected to levers 31 of the pilot valves 32, to operate them.

In Fig. 3, I illustrate another method of operating the pilot valves 32 directly by the 65 pressure in the pipe 13.

The pipe 13 has the branch 51 leading to the first cylinder 52 of a series, there being as many cylinders 52 as there are pilot valves 32, one to operate each valve, I have shown five of such cylinders 52. Each cylinder is 70 provided with a piston 53 on the end of a rod 54 which is connected to the lever 31 to operate the pilot valve 32.

A coiled compression spring 55 is interposed between the piston 53 and a screw 75 cap 56 to normally hold the piston 53 in against the pressure in the pipe 13. I preferably make the springs 55 in each successive cylinder 52 somewhat stronger than the one in the cylinder next preceding. At a 80 sufficient distance from the end of the cylinder 52, in which the piston 53 normally rests, is connected a pipe 57 which connects with the end of the next succeeding cylinder. These pipe connections 57 are made in 85 the same manner between all the cylinders 52 of the series.

In operation, when sufficient pressure is created in the pipe 13 it is exerted against the piston 53 in the first cylinder 52 and 90 compresses the spring 55 and moves the pilot valve 32 to cause the supply valve 35 to be closed. A greater increase in pressure in the pipe 13 will necessarily be exerted against the piston 53 in the second cylinder 95 52, as the piston in the first cylinder has been moved beyond the point where the pipe 57 is connected and allows the free passage of any pressure fluid into the second cylinder 52. Thus it will be seen as the pressure 100 increases in the pipe 13 the pistons in the successive cylinders 52, and, of course, the pilot valves 32 connected to such pistons, will be moved successively.

As the pressure in the pipe 13 diminishes, 105 the last moved piston will be returned to its normal position by its spring 55 first because said spring is exerting greater pressure than the one next preceding, and so on through the whole series of cylinders 52. 110 Instead of having each succeeding spring 55 somewhat stronger to insure the proper successive operations, I may employ mechanical means whereby each piston is locked in its operated position by the operation of the 115 next succeeding piston, and the return of each piston to its normal position will unlock the next preceding piston.

This system of causing successive movements by an increasing or decreasing pressure created by a pump constantly driven by the turbine I claim broadly, whether accomplished electrically or mechanically. 120

The operations as described above can be controlled by the regulating valve 16 in the 125 bypass 15, as it is obvious that by changing the position of the valve the amount of liquid by-passed will be changed, hence the speed of the turbine can be changed.

In order to make this control automatic I 130

may provide another valve 58 in the bypass 15 which is constantly under the control of a governor 59 driven by the same engine that drives the pump 11.

5 As the speed of the engine increases the governor 59 moves the valve 58 and decreases the flow of liquid through said valve, which causes the pressure in the pipe 13 to increase more rapidly than it would without the use 10 of the governor and valve 58.

In accordance with the provisions of the patent statutes, I have described the principle of operation of my invention, together with the apparatus which I now consider to 15 represent the best embodiment thereof; but I desire to have it understood that the apparatus shown is only illustrative, and that the invention can be carried out by other means.

Having thus described my invention what 20 I claim and desire to secure by Letters Patent of the United States is—

1. In a controlling device, a pump, a reservoir, a valve in a by-pass between the outlet of the pump and the reservoir, and means 25 whereby a series of valves are operated successively by either the increase or decrease of pressure produced by the pump.

2. In a controlling device, a pump provided with an inlet and an outlet, a by-pass 30 connecting said outlet and said inlet, a valve in said by-pass controlled by a governor, and means whereby a series of valves are operated successively by either the increase or decrease of pressure produced by the pump, 35 said means comprising pistons connected to said valves and subjected to the pressure of said pump.

3. In a controlling device, a constantly driven pump, and means whereby a series of 40 valves are operated successively by either the increase or decrease of pressure produced by the pump.

4. In a turbine controlling device, a series of pistons subjected to a pressure created by 45 the turbine, each of said pistons being of a different area, and means for yieldingly holding said pistons against said pressure.

5. In a controlling device, a liquid pump provided with an inlet and an outlet, a by- 50 pass connecting said inlet and outlet, a regulating valve in said by-pass, a series of cylinders connected with said outlet, pistons provided in said cylinders, springs provided to normally move said pistons against said

liquid pump pressure, rods connecting said 55 pistons to a series of valves, and means whereby said valves are successively operated by either the increase or decrease of pressure created by said pump.

6. In a controlling device, a liquid pump 60 provided with an outlet and an inlet, a by-pass connecting said outlet and inlet, a valve in said by-pass controlled by a governor, and a series of cylinders of different diameters provided with pistons, said pistons being 65 connected to a series of valves whereby said valves will be operated consecutively by either the increase or decrease of pressure created by said pump.

7. In a liquid pressure controller mechanism for turbines, the combination of valves, fluid motors having differential pistons operatively connected to said valves, means to deliver liquid pressure to said motors, means to vary the pressure of said liquid in said 75 motors, and a reservoir in which the surplus liquid, due to the displacement of said pistons, may be stored.

8. In a governing mechanism, a pump for maintaining a supply of liquid under pressure, a plurality of valves, differential pistons and cylinders for actuating the valves, and a means for regulating the action of the liquid from the pump on the said pistons.

9. In a governing mechanism, a pump for 85 maintaining a supply of liquid under pressure, a plurality of valves, differential pistons and cylinders for actuating the valves, a means for regulating the action of the liquid from the pump on the said pistons, 90 and a reservoir in communication with the pump.

10. In a governing mechanism, a pump for maintaining a supply of liquid under pressure, a plurality of valves, differential 95 pistons and cylinders for moving the valves in one direction, motors for moving them in the opposite direction, and a governor for controlling the action of the said pistons and motors.

In testimony whereof I have signed my name to this specification in the presence of two subscribing witnesses this 10th day of October, 1903.

WILLIAM A. LOUDON.
